UNITED STATES PATENT OFFICE.

CLAIR D. LAKE, OF BINGHAMTON, NEW YORK, ASSIGNOR TO THE TABULATING MACHINE COMPANY, OF ENDICOTT, NEW YORK, A CORPORATION OF NEW JERSEY.

CARD-CONTROLLED COUNTING MACHINE.

Application filed March 3, 1922. Serial No. 540,757.

At the present time, machines are in general use for statistical work which utilize punched cards to designate different statistical data. The points at which these cards are perforated are known as index points and they are commonly arranged in columns upon the cards. By the position of a perforated index point upon the column the desired data is designated. The cards 10 are usually perforated in suitable punching machines and after perforation and comparison they are run through a sorting machine in order to sort them into desired groups. Thereafter it is the practice to run 15 the cards through tabulating machines where the desired data is counted or accumulated upon suitable registers or counters.

In certain classes of statistical work it is 20 desirable to count the number of cards which contain index point perforations at a certain position upon the card. For example, it may be desirable to secure count of cards which have the sixth index point perforation perforated in the second column.

It is to this general end that the present 25 invention is directed. Provision is made for receiving a stack of record cards, setting the machine for control upon any desired column and thereafter successively passing the 30 cards through the machine. During the passage therethrough the machine will sense all cards which have, say the sixth index point, perforated in the second column and disclose upon a suitable counter the total number 35 of cards which have passed through the machine which are thus perforated.

The invention further contemplates the provision of means for counting all cards whether perforated or not passing through 40 the machine and provision of means for counting all perforated cards.

Further and more detailed objects of the invention will be set forth in further detail in the accompanying specification and more 45 particularly pointed out in the appended claims and shown on the drawings which by way of illustration portray a preferred embodiment of the invention.

In the drawings: 50 Figure 1 shows a front view of the machine with the cover or casing removed.

Fig. 2 is a detail sectional view taken on

line 2—2 of Fig. 1 and looking in the direction of the arrows.

Fig. 3 is a similar sectional view taken on 55 line 3—3 of Fig. 1 and looking in the direction of the arrows.

Fig. 4 is a detail sectional view of a part shown in Fig. 1 taken on line 4—4 thereof.

Fig. 5 is a detail view taken on line 5—5 60 of Fig. 4.

Fig. 6 shows a right-hand end view of the resetting handle and the switch which controls the resetting and accumulating of the 65 counters.

Fig. 7 is a detail view showing one of the counters and its associated magnet and controlling cam.

Fig. 8 is a detail sectional view of the parts shown in Fig. 7 taken on line 8—8. 70

Fig. 9 is a diagrammatic view showing card feeding devices diagrammatically and the circuit diagram for the controlling magnets and relays when the machine is at the well known D position on the index. 75

Referring first to the diagrammatic Fig. 9, 10 designates a stack of record cards which are fed one by one by means of a picker 11 to suitable upper feed rolls 12 whence the cards are successively advanced through the lower rolls 13 to the discharge stack, not shown. The feed rolls and picker are all driven in unison by the gearing and linkage shown diagrammatically in this figure. The drive to this gearing is secured 80 through a shaft 15 which in turn receives power from motor 24 by means of suitable belt and pulleys. Rotating in unison with the card feed devices is a main tabulator or counter controlling shaft 19. This shaft is 85 driven in any suitable manner from the gearing which rotates the feed rolls.

In the card feed devices a common conductor bar 38 is provided together with a single sensing or tabulating brush 39. This 95 brush is slidably adjustable along its supporting shaft into alignment with any desired index point column of the record cards which pass through the feeding elements. When a perforation comes under the brush 100 contact is established between the brush and the common bar 38 as is common in tabulating machines of this class. Card feeding devices are therefore provided with a card

lever 50 which has a tip mounted in the path of the passing cards so as to be swung thereby to close contacts 52 and maintain the same closed as long as cards are fed through the machine past the card lever.

Referring to Fig. 3 the shaft 19 extends across the machine under the counter assembly and is shown in dotted lines in this figure. This shaft through suitable gearing 21 drives the lower of three shafts 22 which in turn through the gearing shown in Fig. 2 drives two similar upper shafts 22. These shafts carry cams 23 which constitute the restoring or operating devices for the links to various counters. These counters are of the well known Veeder type. Tabulating cards, as commonly used, have provision for twelve index point perforations, corresponding to the index points designated 1—9, 0, X and R. Twelve counters 24 and two additional ones 25—26 are here provided, 25 being adapted to count the total of all punched cards and 26 the total of all cards whether perforated or not. Inasmuch as the drive for all these counters is identical, one only will be described and the differences in the magnetic control therefore will be later explained.

Referring to Fig. 7, counter 24 is provided with an actuating arm or link 27 which is normally restored to the right by the usual spring inside the counter. Link 27 connects with a pivoted hook member 28 having a shoulder adapted to engage cam 23 and an end portion adapted to be engaged by a latch 29 which forms the armature of a magnet 64. Upon the energization of this magnet the hooked member 28 is released and drops upon cam 23, thereby counting one upon the counter 24. Rotation of cam 23 restores the link 27 and at the proper time in the cycle magnet 64 having been de-energized, the hook 28 is relatched by the latch 29. To insure relatching of the armature or latch 29, a member 30 is provided which is actuated positively by a supplementary cam 31 mounted upon shaft 22 to mechanically knock the armature away from the magnet cores.

Also driven in unison with the shafts 22 is a cam shaft 32 (see Figs. 2 and 3). This shaft carries a number of cams forming part of cam contact devices 62 (best shown in diagrammatic Fig. 9). Twelve of these cam contact devices 62 are provided one for each index point position together with three extra cam contacts marked 78, 72 and 66 in the diagrammatic figure. The cam contacts 62 are timed to operate successively just as the corresponding index point comes under the brush 39.

Passing now to the diagrammatic view Fig. 9, a series of cards are placed in the stack 10. The brush 39 is selectively adjusted to the proper column and the ma-

chine is then ready to count all the ones, the twos, threes, etc., in the cards which pass through the machine. It will be understood that the ones are counted upon one counter 24, the twos on another counter 70 and so on.

To start the machine in operation, the switch 40 leading to a source of current is first closed. Current now flows through line 33 and the emergency stop key 42, now closed, through start key 41, now closed, through motor relay 43, through motor 24 and back through line 34 to the other side of the line. The energization of motor relay 43 through its armature establishes a holding circuit traced as follows: from source through emergency stop key 42 to armature post of relay 45, wire 46, cam contact combination 47, now closed, and back through the armature of relay 43, motor 24 to other side of line. It may be here stated that the cam contact devices 47, 57, 48 and 49 are all individually insulated from each other and driven from a shaft 35 which is geared to rotate in unison with the card feeding devices. The circuit heretofore traced holds the motor 24 in operation and permits the release of a start key.

In all card-controlled machines the machine parts have a normal or home position. This position of parts and the corresponding card position is known as the D position of the machine. This D position is a position which the parts and cards take just after one operation cycle has been completed and before another operation cycle commences. To indicate this position it is the common practice to mark a wheel or index on the machine with the letter D and to provide a suitable pointer cooperating with this index wheel. This wheel is used in timing the machine.

The cam contact devices 48 and 49 make at the so-called D card position. The circuits controlled by these cam contact devices are ineffective until a card passes under card lever 50 which causes a closure of contacts 52. Upon the closure of these contacts current is allowed to flow from source through line 33, cam contact device 48, thence through cam contact device 49, through line 51 to card lever contacts 52, thence through armature binder post 53 of relay 54, through relay magnet 54, wire 55, relay 56, and back through wire 34 to the other side of the line.

The energization of relay 54 establishes a circuit through its armature which through line 56* supplies current to the upper contact 49 thereby shunting out of circuit this cam contact combination. This circuit also shunts out of circuit the card lever contact 52 permitting the last card to pass through the machine to the stacker. Until relay 54 is energized the flow of current to the upper 125

side of switch 40 from this relay is as follows: from relay 54, contacts 52, line 51, contacts 49 and 50, thence to line 33 and to switch 40. After the relay 54 is energized, 5 this current flow through relay 54 can flow through line 56^a to the top of contact 49, thence back through 48 to line 33 and back to 40. Thus the circuit just traced shunts record lever contacts 52 and cam contacts 49 10 and 48 out of control of the circuits previously controlled by them. Cam contact device 57 works in conjunction with cam contact device 48 and serves to break the circuit to relays 54 and 56 once per card 15 cycle, i. e., with contacts 57 and 48 both open there is no flow of current to line 56^a and, consequently, 54 and 49 are deenergized once per card cycle. The energization of relay 56 establishes a holding circuit for the main 20 motor circuit by allowing current to flow through the armature of relay 45, thence through relay armature 56, now closed, through the armature of relay 43 and back through the motor, as previously explained. 25 Relay magnet 56 thus maintains the motor 24 in operation when cam contact device 47 opens once per card cycle. After the passage of the last card, relay 56 will be de-energized permitting the machine to stop 30 when the motor circuit is broken by cam contact device 47.

When relay 54 is energized, current is supplied to the common brush bar 38, and at the time of the passage of the index point perforations in the card under the brush, current will flow from the common bar 38 through brush 39 to line 60. This line 60 extends across and connects in parallel to the cam contact device 62. As heretofore 35 explained, there is one of these cam contact devices 62 for each index point perforation position in the record card. Also these cam contact devices 62 are timed so as to make contact at the time a corresponding perforation passes under the brush. If, for 40 example, the #6 perforation passes under the brush, the cam contact device 62 above the #6 magnet will be closed just as this perforation passes the brush. Switches 61, 45 which will be hereafter further described, being closed, the closure of cam contact device 62 establishes a circuit to a relay 63 energizing this relay and thereby establishing a locking circuit and also energizing selected magnet 64. Relays 63 are those 50 commonly used in tabulating machines and are known as the magnet relays. Their purpose is to maintain the magnets energized after the passage of the brush from the hole in the card. For a further description 55 of their operation see Hollerith Patent No. 945,236. This magnet 64 calls into action its particular counting device in the manner heretofore described. In connection with the description of Fig. 7, it will

be understood that there is one of these magnets 64 for each index point position and for convenience in the diagram Fig. 9 the relays 63 controlling their respective magnets 64 have been individually numbered to correspond with the index point positions with which the magnets are adapted to operate. The circuit for the relays 63 will be traced in detail hereafter. 50 From magnets 64 (4-5-6-7-8-9 positions) current flows through a common line 65, through cam contact device 66, which has the function of breaking the circuit after any one of the above mentioned positions are set for the adding operation. 55 From this cam contact device the circuit extends to a relay 67 and thence back through wire 34 to the other side of the line. Also from magnet 64 (R-X-0-1-2-3 positions) current flows through a common wire 65^a to relay 67, and thence back through wire 34 to the other side of line. Cam contact device 72 breaks this circuit after any one of these mentioned positions are set for adding operation. 60 The cam contact device 72 breaks the circuit 65^a by opening the supply circuits 73 and 68 for the holding relays correlated with magnets 64 (R-X-0-1-2-3 positions). It will be understood that after cam contacts 62 open magnets 64 are 65 supplied with current through the relays associated with the magnets. This cam contact device 72 has a further function to be described hereinafter. The circuit for relays 63 comprises two sections, one having a common line 68 and the other having a common line 69. Line 68 extends to the contact point of the relay 70 and line 69 extends to post 53 of relay 54. When the relay marked 6 of the sixty-three series is 70 energized, relay 67 is energized also and this latter relay is maintained energized by the energization of the relay 6 of the sixty-three series. Relay 67 attracts its armature and establishes a circuit traced as follows: from post 53 through wire 71, cam contact combination 72, now closed, back through wire 73, wire 74, armature of relay 67, now closed, relay 70, relay magnet 75, relay magnet 76 to the other side of the line. Relay 70, 75, when energized, attracts its armature and establishes a holding circuit short-circuiting wire 74. The circuit just traced through relays 70, 75 and 76 is indirectly used to control the total card counter and the total 80 punch card counter heretofore referred to. After this control is secured once per card cycle, cam contact 72 interrupts the circuit through wire 71. Relay 76, when energized, breaks a circuit which is used to control the ringing of a bell 77 and the stopping of the machine when a card having no hole perforated therein passes the control brush. This operation will be here- 85 after described.

The energization of relay 75 and the attraction of its armature establishes a total punched card controlling circuit, traced as follows: from point 53 through wire 71, 5 cam contact device 78, now momentarily closed, wire 79, punched card counter controlling magnet 82, wire 81, armature of relay 75, now closed, total card counter controlling magnet 80, and back to the other 10 side of the line. The above circuit, by the energization of the magnets 80 and 82 controls the stepping or advancing of the total punched card counter 25 and of the total card counter 26 in the manner heretofore 15 explained.

If a card which contains no perforation passes under the controlling brush 39 there will be no energization of the relays 63 and 67. Therefore relays 70, 75 or 76 will not 20 be energized and when cam contact devices 78 close, a circuit is established as follows: from post 53 through wire 71, cam contact device 78, wire 79, relay 83, armature of relay 76, switch 84, and back to the 25 right side of the line. If the switch 84 is thrown to the position shown, the punched cards are counted on both counters 25 and 26 controlled respectively by magnets 82 and 80 and the blank cards would not be counted 30 at all.

If, on the other hand, the switch 84 is thrown to the dotted line position, the magnet 82 will still remain out of circuit upon the passage of a blank card and its punched 35 card counter 25 will be ineffective. Under these conditions magnet 82 fails to operate inasmuch as 75 does not become energized and the magnet 82 can receive no current through line 81. However, with switch 84 40 thrown to the dotted line position magnet 80 will be energized upon the passage of blank cards. With blank cards passing and with the switch 84 in dotted line position, current will flow from 78, wires 79, 83, armature of 45 relay 76, switch 84, wire 75^a, magnet 80 and back to the other side of the line. Thus magnet 80 may be energized on the passage of each blank card as well as on the passage 50 of each punched card and if switch 84 is adjusted to the position shown in full lines in the diagram the magnet 80 will be energized only on the passage of punched cards. Irrespective of the position of switch 84 magnet 82 will be energized only upon the 55 passage of punched cards.

When 83 is energized on the passage of blank cards its armature is attracted, establishing a circuit traced as follows: from source through wire 33, stop key 42, post of 60 start key 41, through wire 86, through contact point and armature of relay 83, through relay 87 back through relay 45 to the other side of the line. Relay 87, when energized, 65 establishes the usual holding circuit through its relay to wire 86 and keeps current flow-

ing through 45 after 83 becomes deenergized. This holding circuit of relay 87 also establishes a circuit through the bell 77 back to the line and keeps this bell ringing continually until the emergency stop key 42 is depressed. 70 The depression of this key opens circuit 86 thus deenergizing relay 87 and opens the bell circuit and thus stops the ringing of the bell. When relay 45 is energized its armature is attracted away from the contact 75 breaking one of the holding circuits for the main motor relay 43. Thereafter upon the opening of the cam contact device 47 the one remaining holding circuit for the main motor relay 43 is interrupted thereby bringing the motor and the card feeding and counting device operated thereby to a stop. 80

As previously explained, the selection of the column upon which the count is to be made is secured by shifting the position of brush 39. In some cases it may be desirable not to count holes above a certain position in the index point column. For example, it may be desired not to count passing cards having any holes which are numbered 1, 2, and 3. This result may be secured by opening the corresponding 1, 2 and 3 switches 61. If, for example, the three upper index points are not to be counted the first three switches 61 from the left in the 90 diagram are opened and the others left closed. If, on the other hand, the lower nine positions are not to be counted the first three switches are closed and the other nine opened. Any combination of these switches 95 may be selected, as desired, thereby eliminating the counting of any particular index point position as desired from top or bottom of the card. In the machine, as constructed, the switches 61 are preferably in the form of canopy switches and one of these is shown in Fig. 2.

To reset counters 24 and 25 two resetting shafts 91^a and 91 are provided. These shafts carry reset gears 92 which mesh with gears 93 which are disposed upon the individual counters so that upon the rotation of the shafts the counters 24 and counter 25 are reset to zero. To rotate shafts 91 and 91^a a handle 90 is fixed on the end of shaft 91. To drive shaft 91^a in unison with shaft 91, from shaft 91, gearing 91^b, 91^c and 91^d is provided. It follows that upon the rotation of the handle 90 all of the counters 24 and counter 25 are reset simultaneously. To ensure resetting, the gearing arrangement is such that one rotation of the handle 90 effects a double rotation of the shafts 91 and 91^a and thus resets the counters twice 110 to ensure accuracy of resetting. 115

The total punched card counter 25 is reset with the counters 24 and the total or all card counter 26 may or may not be reset simultaneously with the resetting of the counters 24 and 25. To control whether this counter 120 125

26 is to be reset or allowed to go on accumulating, a lever 95 (Fig. 6) is provided which rocks a shaft 96 (Fig. 4). This shaft carries a cam block 97 which when in the position shown retains a shouldered pivoted plate 98 on 91^a in upper position. With this position of the parts, gear 99 which revolves on a stud riveted into plate 98 is in mesh with one of the reset gears 92 and this gear 100 through intermediate gear 100 free on shaft 91^a will reset the counter 26 to zero. If, on the other hand, the lever 95 be thrown to lower or accumulating position, cam block 97 will be rocked clockwise allowing plate 98 to swing downwardly under the power of spring 101 and disengage gear 99 from gear 92. Spring 101 at its lower end is fixed to a plate carried on shaft 91^a (see Fig. 4). Under these conditions the counter will not be reset. To prevent the disengagement of the gear at improper times and to ensure their proper timing a Geneva stop interlock is provided. This consists of a disc element 102 having an arcuate slot 103 which is fastened to shaft 91. This disc element cooperates with a locking ring 104 which is carried by shaft 96 which, as heretofore explained, is rocked by handle 95. These devices prevent improper disengagement of the resetting devices for counter 26 at improper times. To prevent repeat resetting operation a latch 105 (Fig. 5) is provided which cooperates with a suitable pin carried by handle 90.

From the foregoing it will be understood that the counters 24 may be utilized to count one per passing card per index point perforation. There is one counter 24 for each different index point perforation in a given column on the card. By adjusting the brush 39 the desired column may be selected. Counter 25 is utilized to count all passing punched cards only. This counter is reset simultaneously with the resetting of the counters 24. Counter 26, on the other hand, is utilized for counting all cards whether punched or not and the resetting devices are of such nature that this counter may be reset at the end of a card group or may be allowed to go on and accumulate a total of the punched cards of the next group. The switch 84 is utilized to control the operation of counter magnets 82 and 80. If this switch is in the position shown in the diagram Fig. 9, the punched cards are counted on both counters 25 and 26, and the blank cards would not be counted at all. If, on the other hand, the switch is thrown to the dotted line position the magnet 82 will be cut out of operation thereby rendering the punched card counter 25 ineffective when the card which is not punched passes under the sensing brush and a signal in the form of bell 77 is automatically rung and this signal is kept in operation even after the machine

stops as previously described and until the emergency stop key 42 is depressed, thereby interrupting the bell circuit and the holding circuit.

After the last punched card passes 70 through the machine and no more cards follow, the card lever 50 opens contacts 52 thereby opening the circuit to relays 54 and 56. In turn armature contacts of relay 56 open the first holding circuit to motor 24 75 and then cam contacts 47 open the second or last holding circuit for motor 24 and the machine will come to a stop automatically, but in no positive position, there being no clutch or stop position on this machine. 80

Briefly summarized the operation and object of the machine is as follows.

A group of record cards is placed in the stack. Some of these may be punched and others may be blank cards. The operator 85 now places brush 39 on a selected index point column. If it is desired to count the number of cards perforated at all the index points in this column all the switches 61 are closed. If counting is not desired on all index point positions any selected switches 61 may be opened to suppress the counting on corresponding positions. The machine is now started in operation by depressing start key 41. The counters 24 now tally, count 90 or register the number of cards which pass through the machine with corresponding point positions therein. Simultaneously with this operation counter 25 counts, registers or tallies all passing punched cards 100 irrespective of whether the index point perforations come in the index point column.

The counter 26 is also adapted to count the punched cards passing through the machine and if switch 84 is thrown to the dotted line 105 position this counter will also serve to count both punched cards and passing blank cards. Should blank cards pass through the machine with the switch 84 in dotted line position a bell or audible signal will be sounded 110 and the sounding of this signal maintained until the operator depresses the emergency stop key 42, thus stopping the operation of the machine.

What I claim is—

1. In a record card-controlled machine in combination with registering devices controlled by the perforated index point perforations in the record cards, means in said machine for giving an audible signal upon 120 the passage of an unpunched card therethrough whereby the operator may be apprised of the presence of such unpunched card.

2. In a card-controlled tabulating machine of the class described, in combination, means for feeding cards successively through the machine, means for sensing the perforations upon any selected column in the card, a plurality of counters, one for each index 130

- point position, means for actuating said counters once for each corresponding index point passing the aforesaid sensing means, a counter for all punched cards and ineffective 5 upon blank cards, and means for operating the same to show the total of all passed punched cards, a total card counter and means for operating the same to show a total of all cards whether perforated or not, 10 and means for suppressing the count upon one or more index point positions in a particular column.
3. In a record card-controlled machine in combination with registering devices controlled by the perforated index points of passing record cards, means for adjusting certain of said devices for alternatively registering the passage of punched cards and blank cards or punched cards only, and 15 means operative when the said adjusting means is adjusted to said latter position for giving an audible signal upon the passage of a blank card through the machine.
4. In a card-controlled tabulating machine 20 of the class described, means for feeding perforated cards through the machine, means for setting the machine for control upon any desired index point column, a plurality of counters, one for each index point 25 position, a total punched card counter and a total card counter, and means controlled by the index points of passing cards for operating each respective index point counter once for each passing card having a corresponding index point perforation therein 30 and means for operating the total punched card counter once for each passing card having a perforation therein and suppressing the operation thereof upon the passage of 35 a blank card, and means for operating the total card counter once for each passing card irrespective of the perforations or lack of 40 perforations therein.
5. In a tabulating machine, in combination, means for successively feeding perforated cards through the machine, means for counting upon a suitable counter the number of punched cards having a determined index point perforation therein, 45 means for counting upon other counters the number of cards having other index point perforations, means for operating a signal when a card which is not punched passes through the machine, means for stopping the 50 machine and means for maintaining the operation of the signal until manually suppressed.
6. In a card-controlled tabulating machine having a card feeding means and an index point perforation sensing means, in combination, a plurality of index point counters controlled by said sensing means and adapted to each count one per passing 55 corresponding index point perforation, a total punched card counter adapted to 60 count the number of all passing perforated cards and to omit the counting of all passing blank cards, a total card counter adapted to count the number of all passing cards whether perforated or not, and means for rendering the punched card counter ineffective on the passage of blank cards. 70
7. In a card controlled tabulating machine of the class described having a card feeding means and an index point perforation sensing means, means including a plurality of separate counters corresponding to the index points for counting the totals of passing cards which are perforated according to the different index point positions, electric 75 magnetic means for controlling the actuation of said counters, mechanical means for positively actuating the said counters and means for simultaneously resetting all of the said counters to zero. 80
8. In a card controlled tabulating machine of the class described having a card feeding means and an index point perforation sensing means, means for accumulating upon separate counters corresponding to the index 85 points the totals of passing cards which are perforated according to the different index point positions, a punched card counter adapted to count all passing perforated cards and to omit the counting of blank cards, and means for simultaneously resetting all the index point counters and the punched card counter to zero. 90
9. In a card controlled tabulating machine of the class described having a card feeding means and an index point perforation sensing means, means for accumulating upon separate counters corresponding to the index points the totals of passing cards which are perforated according to the different index point positions, means including 95 selectively manipulable switch devices for suppressing the count upon any desired index point counters, a total card counter adapted to count all passing cards whether 100 perforated or not and means for simultaneously resetting all the index point counters and said total card counter to zero. 105
10. In a card controlled tabulating machine having card feeding means and index point sensing means, in combination, a plurality of counters corresponding to the different index point positions, means controlled by the sensing means for controlling the same, whereby each of said counters will 110 accumulate the totals of passing cards which are perforated according to the corresponding index point positions, a punched card counter for counting all punched cards irrespective of the position of their index point 115 perforations and to omit the counting of the blank cards, a total card counter for counting all passing cards whether perforated or not, means for resetting the index point counters to zero, and means for resetting the 120
- 125
- 130

punched card counter and the total card counter to zero.

11. In a card controlled tabulating machine having card feeding means and index point sensing means, in combination, a plurality of counters corresponding to the different index point positions, means controlled by the sensing means for controlling the same, whereby each of said counters will 5 accumulate the totals of passing cards which are perforated according to the corresponding index point positions, a punched card counter for counting all punched cards irrespective of the position of their index point 10 perforations, a total card counter for counting all passing cards whether perforated or not, means for resetting the index point counters to zero, means for resetting the punched card counter and the total card 15 counter to zero, and means for rendering the punched card counter ineffective on the passage of blank cards.

12. In a card controlled tabulating machine having card feeding means and index 20 point sensing means, in combination, a plurality of counters corresponding to the different index point positions, means controlled by the sensing means for controlling the same, whereby each of said counters will 25 accumulate the totals of passing cards which are perforated according to the corresponding index point positions, a punched card counter for counting all punched cards irrespective of the position of their index point 30 perforations, a total card counter for counting all passing cards whether perforated or not, means for resetting the index point counters to zero, means for resetting the punched card counter and the total card 35 counter to zero, and means for rendering the resetting means for the total card counter ineffective when it is desired to accumulate a number of punched cards in a plurality of groups on the total card counter.

40 13. A card controlled tabulating machine having in combination card feeding means and a punched card counter having provisions for counting the number of punched cards which pass through the machine, said 45 counter having provisions for omitting the counting of passing blank cards.

14. In a card controlled tabulating machine having card feeding means and index point sensing means, in combination, a plurality of counters corresponding to the different index point positions, means controlled by the sensing means for controlling the same, whereby each of said counters will 50 accumulate the totals of passing cards which are perforated according to the corresponding index point positions, a punched card counter for counting all punched cards irrespective of the position of their index point 55 perforations, said counter having provisions for omitting the counting of blank

cards, a total card counter for counting all passing cards whether perforated or not, means for resetting the index point counters to zero, and means for interrupting the drive for the machine when the last card has 70 passed the sensing means.

15. A perforated record controlled machine comprising in combination, means for sensing the record cards, an audible signal device and means controlled by the aforesaid means and called into operation only in the event that an unpunched card passes through the machine in cooperation with the aforesaid sensing means for bringing about an operation of said audible signal. 80

16. In a perforated record-controlled machine, comprising means for sensing the record cards, means controlled by the aforesaid means for giving an audible signal upon the passage of an unpunched card through the machine, and means for maintaining the said signal device in operation until the operator 85 stops the operation of the machine.

17. A card controlled tabulating machine including in combination with a plurality of index point counters, a total card counter, a punched card counter, electrical means for controlling the operation of said counters, and selective devices manipulable by the operator for suppressing the operation of certain selected counters and for suppressing certain forms of counting operations only, 90 upon another determined counter. 95

18. A card controlled tabulating machine with provisions for handling punched cards and blank cards, said machine having a plurality of counters, means for controlling the operation of said counters, said means having provisions for alternatively counting punched cards on a plurality of said counters and omitting the counting of blank cards on all counters or for effecting counting of punched cards only upon one counter and for effecting the counting of both blank cards and punched cards upon another counter. 100 105 110

19. In a card controlled tabulating machine in combination with means for handling punched cards and blank cards, a plurality of index point counters, a plurality of supplementary counters adapted to each count the total number of punched cards handled by the machine, and means for adjusting the machine to cause one of said supplementary counters to count blank cards as well as punched cards. 115 120

20. A tabulating machine having a plurality of index point counters, a total card counter, electromagnetic controlled means for controlling the operation of said counters, means for positively actuating said counters under the control of said electromagnetic means, and means for suppressing the operation of any index point counter as selected by the operator. 125

21. A tabulating machine having a plu- 130

rality of electrically controlled index point counters, an electrically controlled total card counter, and means for concurrently resetting all of said index point counters and 5 said total card counter.

22. The invention set forth in claim 21 in which means is provided for suppressing the resetting of the total card counter at the will of the operator.

23. A card controlled tabulating machine 10 having in combination with a plurality of index point counters, a plurality of supplementary counters for counting passing punched cards and passing blank and 15 punched cards, means for concurrently resetting all of said counters and adjustable means for rendering ineffective the resetting means for one of the supplementary counters whereby said counter may be used for 20 counting a plurality of groups of cards.

24. The invention set forth in claim 23 in which means is provided to suppress resetting upon the counter which counts both blank cards and punched cards, said means 25 when operated being adapted to permit the concurrent resetting of the index point counters and the supplementary punched card counter.

25. A perforated record controlled machine comprising in combination with record 30 sensing means, an audible signal, means controlled by the aforesaid means for calling said audible signal device into operation upon the passage of an unpunched card through the machine, said last mentioned 35 means having provisions to render the operation of said audible signal ineffective on the passage of the usual perforated cards through the machine.

26. A perforated record controlled machine 40 comprising in combination with devices controlled in one way upon the passage of punched cards through the machine and other devices differently controlled upon the passage of unpunched cards therethrough, 45 a common sensing means for both punched and unpunched cards, said sensing means having provisions for controlling both of the said devices, an audible signal, and means controlled by the second of the aforesaid devices for calling said signal device into operation.

In testimony whereof I hereto affix my signature.

CLAIR D. LAKE.
